UNITED STATES PATENT OFFICE

136,739

DESIGN FOR AN INCENSE BURNER

Frank A. Hoff, Baltimore, Md.

Application September 18, 1943, Serial No. 111,160

Term of patent 14 years

To all whom it may concern:

Be it known that Frank A. Hoff, a citizen of the United States, residing at Baltimore, State of Maryland, has invented a new, original, and ornamental Design for an Incense Burner, of which the following is a specification, reference being had to the accompanying drawings, forming part thereof.

Figure 1 is a front view, showing my new design for incense burners,

Figure 2 is a side elevational view thereof,
Figure 3 is a rear elevation of Figure 1, and
Figure 4 is a sectional view taken along line
4—4 of Figure 3.

I claim:

The ornamental design for an incense burner,
substantially as shown.

FRANK A. HOFF.
